BRUSH MOUNTING FOR DYNAMOELECTRIC MACHINES

Christ Reinker, Lakewood, Ohio

Application September 5, 1946, Serial No. 695,010

3 Claims. (Cl. 171—323)

1

This invention relates to rotary machines for converting electric energy into mechanical energy and vice versa, or in other words, dynamoelectric machines, and especially to brushes and brush contactors for heavy duty motors and generators.

Heretofore, many types of brush contactors have been suggested, but substantially all of the contactors now in use for heavy duty machines have comprised some type of a flat contact bar that in some instances might carry a convex contact button, and with the contact bar or button arranged to be resiliently urged against the end of a brush. In all events, the brush would be mounted for radial movement with relation to the rotor of the machine and be resiliently urged against the commutator by suitable spring contact means. Thus, as the brush wore away, the contactor would still be urged against the outer end of the brush to maintain electrical connection therewith and to retain the brush against the commutator. One difficulty with this present style of brush contacts has been that the contacts wear the brush away unevenly and are apt to cause arcing and undesired high resistance at the region of contact with the brush.

The above difficulties of brush contacts have been increased recently due to use of transversely split brushes in each brush holder. To reduce resistance to current flow as much as possible, the contactor surface should bear on both parts of such sectional brush simultaneously, continuously and, as nearly as possible, uniformly throughout the life of the brush. Usually, some type of shunt wire is connected between the parts of the brush to render them operatively integral for current transmittal.

The general object of this invention is to avoid and overcome the foregoing and other disadvantages of and objections to known types of brush contactors and to provide a brush and contactor or follower therefor that are adapted to provide good electrical contact for their entire service life.

Another object of the invention is to provide a faceted type of brush contactor for equalizing brush wear.

A further object is to provide an improved, inexpensive brush contactor that can easily be used to replace present standard brush contactors.

Another object of the invention is to provide a brush and a brush contactor having substantially complementarily formed contacting sur-

faces curved in the direction of rotation of the motor.

A further object of the invention is to provide a freely movable brush contactor adapted to maintain uniform contact with a relatively large amount of brush surface regardless of the manner in which the brush wears or becomes eroded by arcing.

Another object of the invention is to urge the sections of a laminated brush into mutual contact and dispense with shunt connections between the brush sections.

The foregoing and other objects and advantages of the invention as further explained below are preferably achieved by the provision of a brush having a cylindrically convex outer end, a contact arm, means resiliently urging the contact arm towards the outer end of the brush, and a contact block having a cylindrically concave surface adapted substantially to mate with the convex end of the brush, the contact block being slidably and rockably carried by the contact arm for floating and pressure-equalizing engagement with the convex brush end.

25 In the accompanying drawings:

Fig. 1 is a vertical sectional view through a brush mounting assembly of an electric motor or generator embodying the principles of the invention;

Fig. 2 is a fragmentary vertical section on line 2—2 of Fig. 1;

Fig. 3 is a fragmentary view of an assembly similar to Fig. 1, showing, partly diagrammatically, the contactor and brushes in two relative positions, the contactor being slightly modified with respect to Fig. 1;

Fig. 4 is an enlarged elevational view similar to Fig. 1 further illustrating the invention;

Fig. 5 is a fragmentary side elevation of modified forms of contactor and brush respectively, the latter being partially shown;

Fig. 6 is a transverse sectional detail view as indicated at 6—6 on Fig. 5;

Fig. 7 is a view similar to Fig. 5, showing a further modification of brush contactor; and

Fig. 8 is a sectional detail view thereof as indicated at 8—8 on Fig. 7.

Referring further to the drawings, a conventional commutator 1, as in a direct current electric motor, has the usual arrangement of parallel conductor bars 2 and insulating spacers 3. The commutator bars are in sliding contact with the brush 10 which, in the particular form shown, is of the laminated type being split or having individually movable face-to-face sec-

tions 11 and 12. The radially outwardly facing ends of the brush sections are curved to complement each other in forming a cylindrically convex surface 13. The convexity is in the general direction of rotation of the commutator 1, and the convex surface 13 is uniform for the entire width of the brush. The brush unit, as usual, is rectangular in transverse section (not illustrated).

The laminated brush construction in connection with the contactor arrangement hereof may include any suitable number of laminations or brush plates. As suggested in Fig. 5, two sections 11a and 11b are complemented by two sections 12a and 12b to form a multiple plate brush assembly. The pair of sections 11b and 12b have identical curvatures on the top and the pair 11a and 12a have identical curvatures but different from those of 11b and 12b. The contactor enables use of any number of sections without section-connecting shunt wires such as heretofore usually considered necessary in laminated brush assemblies.

The brush sections 11 and 12 are received in and positioned for radial movement with respect to the commutator 1 by a housing 14 which is rigid with a main hollow metal support or body 15 of bronze or other efficiently conductive metal. Usually, the body 15 has a plurality of radially extending brush guiding portions 14 fitting respective brushes which may, for instance, be arranged in pairs laterally spaced apart in edge to edge relation. The supporting body 15 of the brush mounting assembly is carried on the motor frame (not shown) by suitable supporting posts 16 (one illustrated in Fig. 1), having the usual insulating portion or sleeve 17.

The principal feature of the present invention may be wholly embodied in the contactor block or shoe 18 which has, on the side facing the commutator, a concave face 18a adapted intimately to mate with the outer convex end of the associated brush or which may be of somewhat wider curvature as illustrated in Fig. 1. The cylindrically concave surface 18a is, of course, positioned in the same direction as the convex surface of the adjacent brush end.

A concomitant feature of the invention is that the contact block or shoe 18 is movably guided and supported with relation to the brush unit 10 in a direction tangentially of the rotor and its commutator, and preferably additional limited movement of the contact block is provided. The contact block or shoe 18 is supported on the usual flat sheet metal contact arm 21, which is provided with suitable resilient means, to be later described, urging it toward the commutator.

For supporting the contact block against the brush unit, as shown particularly by Figs. 1 and 2, the contact block has upwardly and inwardly turned flanges 19 at its opposite sides, thus forming a partially closed channel 20 on the top face of the block which slidably receives the contactor arm 21. The channel is of such proportions with relation to the cross section of the contact arm that its walls loosely engage the arm and enable the contact block to rock such slight amount as may be necessary to compensate for unevenness of brush end surface or, as illustrated by Fig. 4, to compensate for wearing away of one brush section 11 or 12 faster than an adjacent brush section wears. Very little rocking or universal movement is necessary for that purpose since the brush sections tend to wear evenly.

In Fig. 4, the contact block 18 has rocked

slightly clockwise on the contact arms 21 in compensating for the lowered position of the top curved end of the brush section 11 relative to the top end of the section 12. This rocking movement maintains adequate pressure and conductive contact between the concave and convex faces of the contact block and brush, as the brush sections wear away.

For adjusting contact pressure between the contact block and the brush, the contact arm 21 is carried on a pair of parallel pivot plates 22 (one shown) which, in turn, are mounted for free turning movement on a cross pin 23 suitably carried in the side walls of the body 15. A spiral spring 24 is connected to the body at one end as by rivets 24a (one shown), and to the contact arm assembly as through a sleeve 25. The sleeve is turnably mounted in the ears 22 and one end of the sleeve rigidly carries a ratchet wheel 26. The spring tends to turn the ratchet wheel counter-clockwise and the spring force is transmitted to the arm 21 through one of its mounting ears by reason of a pawl 27 pivotally carried as on a pin 28 bridging the two mounting ears 22. The spring force may be adjusted by releasing the pawl and turning the ratchet wheel clockwise or counter-clockwise for increase or decrease of brush contact pressure.

Usually in the type of brush mounting assembly illustrated, the contact arm 21 has a flexible shunt connection with some electrically conductive part of the body 15. One improvement represented by the present arrangement is the provision of such shunt connection directly with the contact block 35 or shoe 18. As shown, a flexible metal conductor ribbon or strap, for example braided wire 30, is fixed to a rearwardly extending projection 31 of the block, fastened in place as by riveting or brazing.

The preferred manner of fastening the shunt wire to the block 18 is as shown in Fig. 4, wherein a rivet 30a fastens the wire against the under face of the projection 31. This avoids the expense of slotting the projection as illustrated in Figs. 1 and 3.

The flexible shunt connector strap 30 preferably extends from the contact block rearwardly loosely around the cross pin 28 and then loops forwardly for connection to the body 15. The end 50 of the strap remote from the contact block may, for example, be secured as at 32 by the same rivets 24a as secure the fixed end of the spiral spring 24.

In order to limit the sliding movement of the contact block along the contactor arm 21, the free end of the contactor arm may be turned downwardly to form an abutment flange 34 for preventing the contact block from being moved further than desired outwardly along the contact arm. Additionally, to limit the movement of the block toward the pivotal support of the contact arm, a pin such as 35 may be provided on the contact arm. The limiting abutments are spaced apart wide enough so that the contact block is free to travel whatever distance it has to along the contact arm in order to remain in contact with the brush unit as it becomes worn. Note that in Fig. 3 the contact block 18 in the full-line-illustrated position is closer to the limiting abutment 35 than in the initial position of the contact block shown in broken lines and corresponding to the arm and block position of Fig. 1. The usual lifter arm 36 for the contact arm assembly overhangs the contact block in spaced relation thereto and serves as a guard. The 75 usual electrical feeder connection (not shown)

is secured to the body 15 by the nut and screw assembly 37.

It is not necessary that the concave face of the contact block be continuous. As shown in Fig. 3, a relief groove 33 divides the brush contacting surfaces into separate portions as at 18b and 18c. Fig. 3 further shows that the mutually contacting surfaces of the brush and contact block truly are complementary. It is only necessary for practical accomplishment of the objects hereof that the curved contacting surfaces of brush and contact block substantially mate.

Referring to Fig. 5, the contactor as there illustrated is in two parts, both capable of being made as stampings from metal best suited to the respective parts. The stamping 38 (i. e. copper or bronze) corresponds to the block 18, having a hemi-cylindrical portion 40 for embracing the brush and a flat extension 41 to which a shank portion of the sheet metal part 42 in the form of a clip is secured as by rivets 43. The clip may be of a metal chosen for strength rather than electrical conductivity. The forward end of the shunt wire 30 is clamped between the rivet-secured parts. The clip 42 extends upwardly from the extension 41 over the hemi-cylindrical portion 40 of the contactor part 38 and is there formed into a channeled guide having a base 44, against which the pressure arm 21 bears, and mutually inwardly extending flanges 45 completing a guiding trough for said pressure arm. There is sufficient clearance between the flanges and base so that the contactor assembly can rock as necessary in the manner suggested in Fig. 4, previously described.

In the form shown in Fig. 7, the contactor member 38 supports on its top side and has secured thereto as by the rivets 43 a sheet metal clip 50, the unattached end portion 51 of which is bent upwardly and has a through opening 52 for receiving the pressure arm 21. Again the opening 52 has adequate clearance to enable rocking of the contactor assembly 38—50 through the required limits.

The operation of the arrangement according to Figs. 5 to 8 inclusive is substantially the same as already described in connection with Figs. 1 to 4 inclusive.

From the foregoing, it will be apparent that substantially complementary curved surfaces are formed on the contact shoe and brush unit so that the shoe is free to float, as required, in order to maintain proper electrical contact and adequate radial pressure forces on the end surfaces of the brush. Also, the concave faces 18a, 18b or 18c of the shoe will urge the laminated sections of the brush together when a sectional brush is used.

10 The more intimate contact between the brush sections avoids the necessity for pig-tail shunt connections between the brush sections as now extensively used.

I claim:

15 1. In a brush construction for a dynamo-electric machine having a brush with a convex outer end portion, a contactor member having a concave portion generally complementary to the brush and an arm portion extending therefrom, 20 a sheet metal clip secured to said arm and extending above the concave portion, said clip having an opening through it adapted to receive a pressure arm for holding the concave portion against the brush.

25 2. The contactor device according to claim 1, wherein a shunt wire is secured between the contactor member and the clip.

30 3. The contactor device according to claim 1, wherein the clip has an upstanding free end portion with a generally rectangular opening formed therethrough to receive the pressure arm in edge-wise contact with the sheet metal of which the clip is formed.

CHRIST REINKER.
